DESIGN FOR A DOLL

Sarah E. Barrett, Dayton, Ohio

Application December 3, 1938, Serial No. 81,564

Term of patent 3½ years

To all whom it may concern:

Be it known that I, Sarah E. Barrett, a citizen of the United States, residing at Dayton, in the county of Montgomery and State of Ohio, have invented a new, original, and ornamental Design for a Doll, of which the following is a specification, reference being had to the accompanying drawing, forming a part thereof.

In the drawing:

I claim:

The ornamental design for a doll, as shown.

SARAH E. BARRETT.
